United States Patent Office.

BENJAMIN HILL, OF MALDEN, MASSACHUSETTS.

Design No. 4,703, dated March 14, 1871.

DESIGN FOR THE FRAME OF A SHOW-CASE.

The Schedule referred to in these Letters Patent and making part of the same.

To all persons to whom these presents may come:

Be it known that I, BENJAMIN HILL, of Malden, of the county of Middlesex and State of Massachusetts, have invented or produced a new and useful and ornamental Design for the Metallic Frame of a Glass-Paneled Show-Case; and I do hereby declare the same to be fully described in the following specification and represented in the accompanying drawing, of which—

Figure 1 is a top view, and

Figure 2, a front elevation of one corner portion of such frame.

Figure 3 is a vertical section of it.

In such drawing—

The metallic frame is shown at A as encompassing or fixed to a wooden backing, B, and furnished with a wooden bottom, C, and glass panels or panes, D E, at the top and sides.

The base *a* of the frame, molded as a cyma, as shown, has its corners round, or a continuation of the cyma on the quadrant of a circle, as shown at *b*.

The corner post *c* of the frame, as well as each top rail, *d*, has the form of a sector of a circle in transverse section, the posts and rails at their junction being rounded, as shown at *e*.

The design is the cyma-base rounded at its corner or corners, and the posts and rails formed and rounded at their junction, as shown, constitute the design.

I claim—

The design, as described and represented.

BENJAMIN HILL.
